UNITED STATES PATENT OFFICE.

FRANK ZLAB, OF WILBER, NEBRASKA.

WEIGHT-MOTOR.

1,369,599.

Specification of Letters Patent. Patented Feb. 22, 1921.

Application filed December 10, 1919. Serial No. 343,841.

To all whom it may concern:

Be it known that I, FRANK ZLAB, a citizen of the United States, residing at Wilber, in the county of Saline and the State of Nebraska, have invented certain new and useful Improvements in Weight-Motors, of which the following is a specification.

This invention relates to that class of motors in which a rocking weight imparts rotary direction to a wheel, the rotation of the wheel serving as a source of power for the performance of any desired useful work.

A special object of the invention is to so group and arrange the various parts that a comparatively steady, uniform rotation of the wheel in one direction will be obtained, with the minimum loss of power. A further object is to provide a motor of cheap and durable construction, readily operated by hand, not likely to get out of order, and which can be cheaply and easily repaired, and which will require no special skill in its operation.

With these objects in view the invention consists in the novel features of construction hereinafter described, pointed out in the claims, and shown in the accompanying drawings, in which:

Figure 1 is a side elevation of the machine.

Fig. 2 is a front view, partly broken away.

Fig. 3 is a detail vertical section on line 3-3 of Fig. 2.

In these drawings 1 designates a suitable frame in which is arranged a horizontal shaft 2. On this shaft and within the frame is mounted a wheel 3. The periphery of the wheel is provided with circumferential grooves 4, and as shown in the drawings these are six in number, but any desired number of grooves may be employed depending on the size of the motor and the amount of power desired.

Across these grooves are ruffles or transverse partitions 5. These partitions are staggered with respect to those of adjacent grooves, are suitably spaced, and form, in connection with the grooves, a series of pockets on the wheel tread or face.

A large gear or cog wheel 6 is mounted on the shaft 2, also preferably within the frame and this meshes with the pinion 7, fixed on the shaft 8, which shaft also carries a pulley 9 from which the power is taken.

A shaft 10 is fixed on the top of the frame 1 and suitable bearing plates 11 secure to

this shaft a weight 12 in the form of a metal receptacle having a curved bottom, and which contains some heavy material, such as sand, stones, or the like, as indicated at 13. The receptacle weight 12 is mounted so that it will rock back and forth on the shaft 10 with the minimum amount of friction, the various shaft bearings being of course well lubricated.

To assist in giving uniform and steady rocking movement to the weight 12 I connect thereto metal or wooden straps 14, provided with upper braces 15. These straps support a receptacle 17 which is weighted by stones 18, or other heavy material.

The receptacle 17 and its contents form a weighted pendulum rocking with the movement of the weight 12.

To impart to the wheel 3 the rocking movement of the weight 12 I fix to said weight on opposite sides of the shaft 10 three or more curved plates 19. These plates are in number equal to the number of grooves on the wheel, and whatever their number may be, half of them are on one side of the shaft 10 and half on the other. The upper ends of pushing levers 20 and 21 are pivotally connected to these plates, the levers 21 being secured to the plates 19 on the right hand side of the shaft 10, and the levers 20 being pivotally connected to the plates 19 arranged on the left hand side of the shaft, reference being had to the parts as shown in the drawing. These levers are of unequal length, so that all of the levers on one side of the shaft engage the staggered, transverse partitions 5 of the grooves with which the levers register at the same time.

As the levers on the left hand side engage and push against the partitions during rocking of the weight to the left, they turn the wheel 3 a certain distance in one direction. During this movement the levers 21 on the right hand side are being lifted or drawn upwardly in position to engage partitions on the right hand side of the wheel 3 which will further advance the wheel as the weight rocks back to the right hand side, and during this movement the levers 20 will be retracted and brought into position to engage new partitions and further turn the wheel as the weight again swings to the left.

The gear 6 not only acts to transmit motion to the power shaft 8 but also on account of its size will act as a fly wheel. A motor

of this type is especially adapted to light work around a farm where power is required only for short intervals of time, as in churning, pumping water or running feed

5 cutters, corn shellers and the like.

The weight 12 is hand operated and any form of operating handle can be attached to it if desired.

What I claim is:—

- 10 1. In a weight motor, an oscillating weight, a shaft carrying said weight, a grooved wheel, transverse partitions in the grooves, said partitions being staggered, levers loosely connected to the under side 15 of the weight and arranged in sets, one set being on one side of the shaft and the other set being on the opposite side, the free ends of the levers engaging the partitions of the grooves, and means for transmitting motion from the grooved wheel.
- 20 2. In a weight motor, a grooved wheel, the grooves of the wheel having transverse partitions, offset with respect to each other, an oscillating weight mounted above the

wheel, a series of levers loosely connected to 25 the weight and adapted to engage partitions of a portion of said grooves as the weight swings in one direction, and a second series of levers adapted to engage the partitions of the remaining grooves as the weight 30 swings in the opposite direction, as and for the purpose set forth.

3. In a weight motor, a frame, alining upper and lower shafts, a wheel on the lower shaft having pockets formed on its 35 periphery, a weight normally balanced on the upper shaft, a lever pivotally connected to the weight on one side of the last mentioned shaft and adapted to engage a portion of the pockets, and a second lever pivotally connected to the weight on the opposite side of the shaft and adapted to engage the remaining pockets, said levers engaging wheel pockets alternately as the weight is 40 rocked.

In testimony whereof I affix my signature.

FRANK ZLAB.
